UNITED STATES PATENT OFFICE.

SAMUEL DEAN, OF TOPEKA, INDIANA.

CARPENTER'S GAGE.

SPECIFICATION forming part of Letters Patent No. 638,446, dated December 5, 1899.

Application filed January 30, 1899. Serial No. 703,939. (No model.)

To all whom it may concern:

Be it known that I, SAMUEL DEAN, a citizen of the United States, and a resident of Topeka, in the county of La Grange, State of Indiana, have invented certain new and useful Improvements in Carpenters' Gages, of which the following is a specification.

The object of my invention is to provide an attachment for the framing-squares commonly used by carpenters, by means of which the various angles of cuts may be indicated, the lengths of such cuts shown, and the distance between cuts shown on a framing-timber or in stairwork and the like.

15 A further object is in providing a device of this character that may be cheaply made, easily and quickly adjusted and operated, and which will accurately perform the work for which it is intended.

20 In the accompanying drawings, forming a part of this application, Figure 1 is a perspective view of my invention, showing its application to a square and a piece of timber. Fig. 2 is a detail, partly in section, of one of the 25 clamps used in my device. Figs. 3 and 4 are details of the clamp used in my invention.

Referring to the drawings, A represents a strip of hard wood rectangular in cross-section and preferably about thirty-one inches 30 long. Secured at each end of the strip A by small screws b is the bent-over end of a flat steel plate B of the same width as the strip A. Between the contiguous faces of the strip and plate a space is left in which the square C, 35 of common construction, may be inserted and freely moved.

In the under side of the strip A is formed a longitudinal groove c, which extends throughout the entire length of said strip. In 40 this groove slidingly fit the upturned lower ends e of the clamps H and I, which overhang said strip and are provided with screws h, which are adapted to be screwed down upon the plate B, and thereby binding the square 45 between said plate and the upper side of the strip A in a well-known manner. The clamps

H and I are formed with their lower ends e elongated in order to give a long bearing in the slot in which they slide and are preferably made right hand and left hand, respectively.

On the upper face of the plate B is indicated a graduated scale, one edge of which shows inches and fractions thereof, as at F, and the opposite edge feet and fractions thereof, as at D, thus permitting measurements for large or small boards or timbers and the use of the square on either side of the gage.

In using my device the square is inserted between the plate and the strip, and a given point on the tongue of the square is connected or registered with O or the beginning of the scale F. The clamp H is then brought to a position where the tongue and the strip or gage cross or overlap and firmly screwed in such position. The blade of the square is then brought to a point to register with the scale-figure required and the clamp I moved along and secured at such junction. In this way, one side of an angle being known, the length 70 of the other two sides may be determined and the angles indicated.

Having thus described my invention, what I claim as new, and desire to obtain by Letters Patent, is—

75 A gage attachment for carpenters' squares, consisting of a strip of wood having a longitudinal groove in its under side, a yielding metal plate having scales indicated thereon, said plate being secured to the ends of the wooden strip so as to leave a space between the upper side of the strip and the lower side of the plate, and removable clamps adapted to embrace said plate and strip and having one of their ends adapted to slide in the 80 groove in the strip, and adjusting-screws in said clamps, as set forth.

SAMUEL DEAN.
